United States Patent Office

Des. 193,362
Patented Aug. 7, 1962

193,362

COMBINED PACKAGE AND SERVING CONTAINER

Emory L. Groff, Jr., Bethesda, Md., assignor to Frank A. Buonauro, Union City, N.J.

Filed Apr. 26, 1961, Ser. No. 64,903

Term of patent 14 years

(Cl. D58—25)

FIG. 1.

FIG. 2.

FIG. 3.

FIG. 4.

FIG. 1 is a perspective view of a combined package and serving container showing my new design.

FIG. 2 is an exploded side elevational view thereof.

FIG. 3 is a horizontal cross section taken on the line 3—3 of FIG. 2.

FIG. 4 is a bottom plan view thereof.

I claim:

The ornamental design for a combined package and serving container, substantially as shown.
